(57) **CLAIM**

The ornamental design for a ceiling fan motor housing, as shown and described.

DESCRIPTION

FIG. 1 is a top perspective view of a ceiling fan motor housing in the environment of a ceiling fan, showing my new design;

FIG. 2 is a bottom perspective view thereof;

FIG. 3 is a top view thereof;

FIG. 4 is a bottom view thereof;

FIG. 5 is a front side view thereof;

FIG. 6 is a rear side view thereof;

FIG. 7 is a right side view thereof; and,

FIG. 8 is a left side view thereof.

Portions of the ceiling fan motor housing and the ceiling fan environment shown in broken lines form no part of the claimed design.

1 Claim, 6 Drawing Sheets(56)
